UNITED STATES PATENT OFFICE.

HAROLD F. DUNBAR, OF TURNERS FALLS, MASSACHUSETTS.

PAPER-MAKING MACHINERY.

1,179,411.

Specification of Letters Patent. Patented Apr. 18, 1916.

Application filed July 26, 1915. Serial No. 41,848.

To all whom it may concern:

Be it known that I, HAROLD F. DUNBAR, of Turners Falls, county of Franklin, and State of Massachusetts, have invented certain new and useful Improvements in Paper-Making Machinery, of which the following is a specification.

This invention relates to improvements in paper making machinery.

10 The object of the invention is to provide a device for forming creases in the paper so that when sheets containing these creases are bound into a book form the leaf will more readily bend at the creased portion.

15 Broadly, the invention comprises a series of rolls formed with creases between which and another cylinder the web of paper passes in its travel from the last press roll to the first drying roll.

20 I attain this object by the mechanism illustrated in the accompanying drawings in which—

Figure 1 is a front elevational view looking at that part of the paper making machine toward the last press rolls; Fig. 2 is a side elevational view showing the end of the last press rolls, the paper creasing device and the first drier roll; Fig. 3 is a transverse sectional view on the line 3—3 looking in the direction of the arrows and showing the improvement in detail; Fig. 4 is a detail view of the creasing rolls; Fig. 5 is a side elevational view of the driving mechanism of the paper creasing device, and Fig. 35 6 is a detail view of a slight modification of the elastic mounting of the upper creaser roll.

Referring to the drawings in detail: 1 represents the framework of the machine, 40 2 and 3 the last pair of press rolls that are mounted in the usual manner in the framework of the machine. The upper press roll 2 is provided with means for exerting a suitable pressure on this roll. This means 45 comprises upwardly extending shafts 4 to the upper end of which is secured a hand wheel 5, whereby when the same is rotated the roller 2 can be moved upward. Attached to the bed portion end of the main frame is 50 an upright 6 which supports an overhanging arm 7. Mounted in this arm and in a similar one at the opposite side of the machine are a series of rolls 8 which are designed to support the web of paper, indicated at 9, as it passes to the drier rolls 10. An idler or tension roll 11 is located be-

tween the last roll 8 and the first of the drier rolls. Each of the rolls 8 are provided with a sprocket wheel 12 over which passes a sprocket chain 13. The power for operating the sprocket chain 13 and the web supporting rolls 8 is derived from the sprocket wheel 14 which is secured to a power shaft 15. This shaft is driven from the cone pulley 16 over which passes a belt 17 that is 60 driven from the cone pulley 18. This pulley is mounted on a shaft 19 on the end of which is a pulley 20 which is driven by means of the belt 21. This belt in turn is driven from the large pulley 22 which is 65 secured to the shaft 23, that is directly connected to the lower press roll 3, above referred to. The rate of rotation of the rolls 8 is so adjusted by means of the cone pulleys so as to be slightly greater than the 70 rate of rotation of the press-rolls 2 and 3.

Referring now to the means for operating the two paper web creaser rolls 24 and 25: 26 designates a belt that is driven from the cone pulley 27. This belt drives a second 80 cone pulley 28, that is secured to the shaft 29 on which is secured a gear 30. This gear in turn meshes with the small spur gear 31 and the gear 31 with the gear 32 of equal diameter. The shafts 33 and 34 to which 85 the gears 31 and 32 are secured extend transversely of the machine in parallel relation with the press rolls 2 and 3. The creaser rolls 24 and 25 are therefore driven at the same speed as the rolls 2 and 3. The shaft 90 35 is mounted in adjustable boxes 36, depending from the lower side of which are rods 37. The lower ends of these rods rest on cams 38 that are secured to a shaft 39. This shaft is provided with a hand wheel 95 40 whereby when the same is operated the boxes 36 carrying shaft 35 can be raised and lowered as desired.

It will be necessary to depress the lower creaser rolls 25 in order to permit threading the web of paper 9 through the machine. The rolls 24 and 25 are provided with means for laterally adjusting the same on their shafts. The rolls 25 are secured to the shaft 100 35 by means of the set screws 36, while the roll 24 is connected to the shaft 34 by means of the spline 37. Extending transversely of the machine and above the arm 7 is a connecting bar 38. This bar serves the double purpose of bracing the machine and for supporting a carriage 39' which can be readily locked to the bar 38 by means of the clamp- 105 110

ing arm 40 which is attached to a tightening screw 41. The carriage 39' is slotted as indicated at 42 and is for the purpose of permitting the carriage to be readily clamped to the connecting bar in order to position the roll 24 with reference to the sheet of paper to be creased. Depending from the carriage 39' are bracket arms 43 in which are pivotally mounted arms 44. The arms 10 44 have secured at their ends pivots 45 to which are secured upwardly extending arms 46 on the end of which a block 47 is secured. In Fig. 6 a slight modification is shown, the arm 44' serving the same purpose as 15 the arm 44 in Fig. 3. Located above and below this block are compression springs 48 and 49. The opposite ends of these springs are provided with means for adjusting the tension thereof as indicated by 20 the threaded rods 50 and 51. The arm 44 oscillates about the pivot 52, whereby when the web of paper is passing through the machine the roller 24 can rise and fall in order to compensate for any irregularities 25 in the thickness of the paper.

It should be stated that the belt 21 passes over the belt tightening pulley 21' that is mounted on an arm 21². On the opposite end of this arm is placed a weight 21³ and 30 attached to this weight is a depending arm to which the weight 21⁴ is attached. It will be seen from this construction that the paper creasing device is located between the last pair of press rolls and the first one of 35 the drier rolls. That is to say, the paper is still in a moist condition when the impression of the rolls 24 and 25 is made in the web of paper as it passes through the machine.

40 I am aware that it is not new to form creases in paper at other points in its passage through the paper making machines, but I believe it to be new to locate the creasing rolls at a point in the passage of the 45 web already referred to.

It will be observed that the ridges of the creasing rollers 24 and 25 are located one above the other in the same vertical planes as clearly shown in Fig. 4. It will also be 50 observed that on account of the use of the large number of rollers 8 the web of paper 9 will approach the creasing rolls 24 and 25 in a straight, even horizontal run. The creasing rolls 24 and 25, it will be observed 55 are located intermediate the rollers 8.

What I claim is:

1. A device for creasing a web of moving paper while in a moist condition, comprising, a series of rollers to support the web 60 of paper, means for rotating said rollers at the same speed as the moving web of paper, a pair of rollers having elevations formed on their periphery, said elevations engaging the opposite sides of the web, 65 means for adjusting the pressure of said

rollers, said device being arranged between the last pair of press rolls and the first drier roll of the machine, as described.

2. A paper creasing device comprising in combination, grooved pressure rollers for 70 engaging the opposite sides of a moving web of paper, shafts to support said rollers, means for adjusting one of said rollers, comprising pivotally mounted arms attached to its shaft, means to yieldingly support the 75 ends of said arms, said device being located, as described, between the press rolls and the drier rolls.

3. A paper creasing device comprising in combination, grooved pressure rollers for 80 engaging the opposite sides of a moving web of paper, shafts to support said rollers, means for adjusting one of said rollers comprising pivotally mounted arms attached to its shaft, means to yieldingly support the 85 ends of said arms, said device being located, as described, between the press rolls and the drier rolls, and means for laterally adjusting said rollers relative to the width of the web of paper.

4. A paper creasing device comprising a series of web supporting rolls, a pair of creasing rolls, located intermediate the supporting rolls, said rolls being located between the last pair of press rolls and the 95 first drier roll, whereby the paper is creased while in a moist condition.

5. A device for imparting creases to the opposite sides of a moist web of moving paper and comprising a pair of grooved 100 rollers, the elevations or ridges of said rollers being oppositely located and arranged in the same vertical planes, said rollers being located between the press and drier rolls, and cam devices for elevating and depressing 105 the lower one of said grooved rollers to permit threading the web of paper through the machine as described.

6. A device for imparting creases to the opposite sides of a web of moving paper 110 comprising a pair of grooved rollers arranged on the opposite sides of the web, a plurality of rollers for supporting the web and arranged in a horizontal plane for causing the web to approach the creasing rollers in a straight line, said creasing rollers being located between two of the supporting rollers, means for operating the creasing rollers, means for operating the web-supporting rollers, said device being located between the last pair of press rolls and the first drier roll.

7. A device for imparting creases to the opposite sides of a web of moving paper comprising a pair of grooved rollers arranged on the opposite sides of the web, and in the same vertical plane, a plurality of rollers for supporting the web and arranged in a horizontal plane for causing the web to approach the creasing rollers in a straight 125 line.

line, said creasing rollers being located between two of the supporting rollers, means for operating the creasing rollers at the same speed as the moving web of paper, 5 means for operating the web-supporting rolls, as described, said device being located between the last pair of press rolls and the first drier roll.

8. A device for imparting creases to the 10 opposite sides of a moist web of moving

paper and comprising a pair of grooved rollers, the elevations or ridges of said rollers being oppositely located, said rollers being located between the press and drier rolls, and cam devices for elevating and depressing the lower one of said grooved rollers to permit threading the web of paper through the machine as described. 15
